(57) **CLAIM**

The ornamental design for a vehicle rear lower bumper tow hitch cover, as shown and described.

DESCRIPTION

FIG. 1 is a front elevational view of a vehicle rear lower bumper tow hitch cover, showing our new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a top, front and left side perspective view thereof; and,

FIG. 7 is a bottom, front and left side perspective view thereof.

The ghosted or low contrasted structures in the drawings illustrate portions of the vehicle rear lower bumper tow hitch cover that form no part of the claimed design.

1 Claim, 7 Drawing Sheets
